(57) **CLAIM**

The ornamental design for a pruner, as shown and described.

DESCRIPTION

FIG. 1 is a front perspective view of a pruner showing our new design;

FIG. 2 is a front elevational view thereof, a mirror image of which would constitute a rear elevational view;

FIG. 3 is a top plan view thereof;

FIG. 4 is a bottom plan view thereof; and,

FIG. 5 is a rear elevational view thereof.

The broken line showing of pruner elements is for illustrative purposes only and forms no part of the claimed design.
